UNITED STATES PATENT OFFICE.

CHARLES W. PEARSALL, OF UNION, AND HIRAM B. PEABODY, OF VESTAL,
NEW YORK.

APPARATUS FOR PLACING TORPEDOES ON RAILS.

SPECIFICATION forming part of Letters Patent No. 546,028, dated September 10, 1895.

Application filed February 7, 1895. Serial No. 537,581. (No model.)

To all whom it may concern:

Be it known that we, CHARLES W. PEARSALL, residing at Union, and HIRAM B. PEABODY, residing at Vestal, county of Broome, State of New York, citizens of the United States, have invented certain new and useful Improvements in Apparatus for Placing Torpedoes on Rails; and we do declare the following to be a full, clear, and exact description 10 of the invention, such as will enable others skilled in the art to which it appertains to make and use the same, reference being had to the accompanying drawings, and to the letters of reference marked thereon, which 15 form a part of this specification.

Our invention relates to improvements in an apparatus for placing torpedoes on rails, and has for its object the production of a more efficient and easily-operated device.

20 To this end the main and primary object of the present invention is to improve upon the construction of apparatus for placing torpedoes on rails.

With these and other objects in view which 25 will readily appear as the nature of the invention becomes better understood, the same consists in the novel construction, combination, and arrangement of parts hereinafter more fully described, illustrated, and claimed.

30 Figure 1 is a perspective view of our device with torpedo in position. Fig. 2 is a plan view of one of the springs C. Fig. 3 is a side view of one of the springs C. Fig. 4 is a bottom view of the device with torpedo in position. Fig. 5 shows the application of our device to the rail.

Referring to the accompanying drawings, A represents the handle, made preferably of wood, the lower portion of which has a longitudinal slit B cut entirely through it for the purpose of obtaining a spring, the purpose of which will be hereinafter more particularly stated. On each side and parallel with the said slit are secured to said handle the flat spring-plates C C, extending below the torpedo. These spring-plates are each provided with a recess D D for the reception of the torpedo, as shown in Figs. 2 and 3. From said recess the spring-plate is curved 45 outwardly, as shown in the drawings. The

bottom of said handle preferably presents a flat surface at a right angle with the slit and spring plates, and to this surface is secured a cushion of rubber or other suitable composition on each side of the slit B for the purpose of preventing a premature explosion of the torpedo when being placed upon the rail. Now it will be readily apparent that when the torpedo is placed between the spring-plates C C, in such a manner that the flange 55 of the torpedo engages with the recesses D D of the spring-plates, it will remain in such position until released. When desired to place the torpedo upon the rail, the apparatus is held over the rail in such manner that the 60 spring-plate will, when forced upon the rail, spring outwardly. This spring movement is obtained by the curvature of the spring-plate hereinbefore alluded to; and the slit, to which we have called attention, also aids in obtaining 70 this spring, which serves to release the torpedo when the curved end of spring-plates are brought in contact with the rail. The torpedo is held in position upon the rail by means of the spring thereon, as is in common 75 use.

By the use of this device it is possible to place torpedoes upon the rail from the rear of a train while in motion. We are aware of the fact that there are other devices for accomplishing the above result. Hence we make no broad claim to these features; but

What we claim as new, and desire to secure by Letters Patent, is—

1. The combination of the handle, provided 80 with a longitudinal slit and spring-plates having a recess therein, substantially as illustrated and described.

2. The combination of a handle provided with a longitudinal slit and spring-plates, 90 and cushion substantially as illustrated and described.

In testimony whereof we affix our signatures in presence of two witnesses.

CHARLES W. PEARSALL.
HIRAM B. PEABODY.

Witnesses:

HARRY D. REYNOLDS,
MARY T. LOUGHLIN.
